HEATER

Ewald F. Tobold, Cleveland, Ohio, assignor to
The Dill Manufacturing Company, Cleveland,
Ohio, a corporation of Ohio

Application October 17, 1934, Serial No. 748,672

7 Claims. (Cl. 132—36)

This invention relates to a heater for use in waving hair, and more particularly to a steam heater for that purpose.

An object of the invention is to provide a steam heater tube which may be attached readily, quickly, and securely to a source of steam supply and which may be positioned quickly upon a curling rod and securely clamped or held to the hair of the person receiving the wave.

Another object of the invention is to provide a steam heater tube which is simple and economical to manufacture.

Another object of the invention is to provide a steam heater tube having the material of the tube forming the closure for one end thereof in such manner as to prevent leakage of condensation at such point but at the same time to provide for a slight escape of steam to create a circulation or flow of the steam around the curled hair and to obviate the danger of building up steam pressure within the tube.

Further and additional objects and advantages residing in the invention will become more apparent hereinafter during the detailed description which is to follow of an embodiment thereof, which embodiment is illustrated in the accompanying drawing, wherein:

Fig. 1 shows a heater embodying the invention applied to a person's head and connected to a source of supply of steam;

Fig. 2 is a full size elevational view of the heater as it is positioned upon a curling rod and attached to a person's hair and to a source of supply of steam, certain portions of the tube being broken away and shown in section and disclosing the curling rod with the hair curled thereon within the tube;

Fig. 3 is a full size elevational view of the tube of the heater with the end or closure cap removed therefrom;

Fig. 4 is a transverse sectional view taken substantially on line 4—4 of Fig. 2, looking in the direction of the arrows;

Fig. 5 is an end elevational view of the closure cap; and

Fig. 6 is a sectional view of the closure cap taken substantially on line 6—6 of Fig. 5, looking in the direction of the arrows, the steam supply pipe being shown in position to be inserted into the opening in the cap and secured therein.

The heater of the present invention is of the steam type and comprises a tube closed at one end which receives the curling rod upon which the hair to be curled is wound and the end cap or closure member for sealing the open end of

the tube, said cap or closure member being constructed to receive a fitting on the end of a steam supply pipe.

The tube is formed of suitable material having sufficient rigidity to maintain the shape of the tube, and said material is preferably spirally wound into the cylindrical shape of the tube.

The tube is composed preferably of two different materials, the inner material 10 being such as to absorb moisture and the outer material 11 10 being impervious to moisture, as, for example, aluminum foil. The overlapping convolutions of the materials are secured together with a suitable moisture-proof adhesive.

The provision of the moisture absorbing inner 15 material 10 is of great importance, since the water produced by the condensation of the steam within the tube during use is absorbed by such material. This eliminates the danger of hot water being spilled upon customers as the end 20 cap or closure member is removed from the tube preparatory to sliding the tube off the curling rod and the hair wound thereon.

As previously stated, the tube is closed at one end by the material of the tube itself, this making the tube extremely economical to manufacture, with the result that the cost of the tube is sufficiently low to allow of its advantageous use.

The material of the tube at one end thereof is pressed flat, as indicated at 12 in Figs. 1, 2, and 3, with an amount of pressure sufficient to cause the inner material 10 to adhere and close the end of the tube. In order to further stiffen the closed end of the tube, the flat portion 12 is provided with serrations 13 which may be of any 35 desired shape, although they are illustrated herein as diamond-shaped. The purpose of the serrations 13 is to stiffen the material and make the pressed jointure thereof firm enough to prevent its separation during the steaming operation 40 when the material becomes softened by moisture.

In order to further strengthen the closure provided by the flat pressed portion 12 of the tube, such portion is bent at an angle to the longitudinal center line of the tube, as clearly illustrated in Figs. 1, 2, and 3.

The closure provided at one end of the tube by the pressed flattened serrated portion of the tube material which is angularly bent is sufficiently tight to prevent the leakage of condensation upon the person receiving the wave, particularly since the major portion of the condensate is absorbed by the inner material 10 of the tube. Although the closure is tight enough to prevent the leakage of condensation, it is not so 55

tight as to prevent the slight escape of steam from the tube, whereby a circulation of the steam is created in the tube and a building up of steam pressure therein is eliminated.

5 The end cap or closure member for the open end of the tube is a cup-like member 14, preferably of metal, having in its bottom wall an opening into which is secured a tubular fitting 15 for receiving the steam supply pipe. The fitting 15 has a portion of its bore of such size as to snugly receive a fitting on the end of the steam supply pipe and is provided with an opening extending laterally from the bore in which is movably arranged a ball detent 16. The detent 16 is held normally in a position to have a portion projecting into the bore of the fitting 15 by means of a wire spring 17 engaging the detent and encircling the fitting 15 with one end anchored in the fitting.

The cap or closure member 14 is provided with 20 a slot 18 extending longitudinally inwardly of the member from its open slightly flared end as clearly shown in Fig. 2. In order to maintain the cap or closure member 14 securely on the tube and to prevent its accidental displacement therefrom, the member is provided just inwardly of its open 25 end with one or more barbs or prongs 19 extending inwardly of the member and preferably struck from the material of the member and adapted to dig into the material of the tube.

30 The steam supply pipe is shown at 20 and has a fitting 21 on its end adapted to pass into the fitting 15 of the cap or closure member with a sliding but tight fit, which fitting 21 has a notch 22 into which snaps the ball detent 17 to hold the fitting 21 securely in the cap or closure member.

35 It will be understood that a plurality of the tubes are used when waving a customer's hair, but since each tube is applied in an identical manner, only the application of one tube need be explained.

40 The hair 23 is wound upon a curling rod 24 in a manner well understood, after which the rod with the wound hair thereon is slipped into the tube with the open end of the tube adjacent the customer's head. The cap or closure member 45 14 is then positioned upon the open end of the tube with the strand of hair passing through the slot 18. The open end of the tube is thus sealed while the hair is clamped between the tube and the cap or closure member. The steam supply pipe 20 is then connected to the tube by inserting the fitting 21 into the bore of the fitting 15 carried by the cap 14 until the detent 17 snaps into the notch 22 of the fitting 21.

50 Although a preferred embodiment of the invention has been illustrated and described herein,

it will be understood that the invention is susceptible of various modifications and adaptations within the scope of the appended claims.

Having thus described my invention, I claim:

5 1. A hair waving heater of the steam type comprising a tube open at one end and closed at the other end by a pressed flattened portion of the tube material, and a removable cap closing the open end of the tube and having means for attaching a steam supply pipe thereto in communication with the interior of the tube.

10 2. A hair waving heater of the steam type comprising a tube open at one end and having the material of the tube at its opposite end deformed and pressed together into adherent relationship to form a closure for said end of the tube.

15 3. A hair waving heater of the steam type comprising a tube formed exteriorly of moisture impervious material and interiorly of moisture absorbent material, said tube being open at one end and having the materials of the tube at its opposite end deformed and pressed together into adherent relationship to form a closure for said end of the tube.

20 4. A hair waving heater of the steam type comprising superimposed strips of water-impervious and moisture absorbent materials wound to form a tube, said tube being open at one end and having the materials of the tube at its opposite end deformed and pressed together into adherent relationship to form a closure for said end of the tube.

25 5. A hair waving heater of the steam type comprising a tube open at one end and having the material of the tube at its opposite end deformed and pressed flat together into adherent relationship to form a closure for said end of the tube.

30 6. A hair waving heater of the steam type comprising a tube open at one end and having the material of the tube at its opposite end deformed and pressed flat together into adherent relationship to form a closure for said end of the tube, said closure being disposed angularly with respect to the longitudinal center line of the tube.

35 7. A hair waving heater of the steam type comprising superimposed strips of water-impervious and moisture-absorbent materials wound to form a tube, said tube being open at one end and having the materials at its opposite end deformed and pressed flat together into adherent relationship to form a closure for said end of the tube, said closure being disposed angularly with respect to the longitudinal center line of the tube.

55 EWALD F. TOBOLD.
